OIL COOLER FOR MOTORCYCLES

William C. Hauser, Hacienda Heights, Calif., assignor to
Lockhart Industries, Inc., Paramount, Calif.

Filed June 1, 1973, Ser. No. 366,138

Term of patent 14 years

Int. Cl. D12—11
U.S. Cl. D12—114

FIG. 1

FIG. 2

FIG. 3

FIG. 4

FIG. 5

FIG. 1 is a perspective view of an oil cooler for motorcycles showing my new design;

FIG. 2 is a side elevational view thereof, it being understood that the opposite side is a mirror image of the side shown herein;

FIG. 3 is a front elevational view thereof, it being understood that the rear is a mirror image of the front shown herein;

FIG. 4 is a top plan view thereof; and

FIG. 5 is a bottom plan view thereof.

I claim:

The ornamental design for an oil cooler for motorcycles, substantially as shown and described.
